(57) **CLAIM**

I claim, the ornamental design for a clip for urinary drainage tubing connector, as shown and described.

DESCRIPTION

FIG. 1 is a perspective view of a clip for urinary drainage tubing connector embodying my design.

FIG. 2 is a top plan view thereof.

FIG. 3 is a bottom plan view thereof.

FIG. 4 is a side elevational view thereof.

FIG. 5 is a side elevational view thereof.

FIG. 6 is a rear elevational view thereof; and,

FIG. 7 is a front elevational view thereof.

1 Claim, 7 Drawing Sheets
